UNITED STATES PATENT OFFICE.

JOHN J. LALLY, OF ST. LOUIS, MISSOURI.

FOOT-BLOCKING FOR SWITCH-FROGS.

1,246,439.

Specification of Letters Patent. Patented Nov. 13, 1917.

Application filed March 23, 1917. Serial No. 156,905.

To all whom it may concern:

Be it known that I, JOHN J. LALLY, a citizen of the United States, residing at St. Louis, in the city of St. Louis and State of Missouri, have invented certain new and useful Improvements in Foot-Blockings for Switch-Frogs; and I do hereby declare the following to be a full, clear, and exact description of the invention, such as will enable others skilled in the art to which it appertains to make and use the same.

This invention has for its object to provide a novel and efficient foot blocking for switch frogs and guard rails that will effectively prevent the foot of a person, or any other object, from becoming wedged between the track rail and a guard rail, or between a track rail and a switch rail, and which can be cheaply manufactured, will be durable and can be placed in operative position or removed therefrom in a convenient and expeditious manner.

Other objects will appear and be better understood from that embodiment of my invention of which the following is a specification, reference being had to the accompanying drawings, in which:

Figure 1 is a fragmentary plan view of a railway switch frog, showing two of the main rails and one of the rails of the siding, and showing the improved foot blocking mounted in operative position.

Fig. 2 is a section taken on the line 2—2 of Fig. 1.

Fig. 3 is a perspective view of one of the foot blocks that is to be positioned between one of the guard rails and one of the track rails removed from operative position.

Fig. 4 is a perspective view of the bracket for securing one of the foot blocks to be located between the main rail and siding rail.

Fig. 5 is a perspective view of the bracket for securing one of the blocks between the guard rail and adjacent track rail, and

Fig. 6 is a section taken on the line 6—6 of Fig. 1.

Referring to the drawings in detail, the letter A designates the companion rails of a main track and B one of the rails of the siding. The letter C designates a switch frog located at the point of intersection between one of the main rails A and the wing rail C, shown in Fig. 1, and the letters D and E indicate, respectively, the inside and outside guard rails for the intersecting rails

A and B, shown in Fig. 1. The other rail of the main line is shown in Fig. 1 provided with an inside guard rail F.

Located between the intersecting rails of the main track and siding, and on opposite sides of the point of intersection, is a pair of foot blocks 1. Each of these blocks 1 are substantially triangular shaped in plan, as shown in Fig. 1, and has the inner or smaller end thereof extended upwardly in the direction of the walls of the adjacent rails and thence extended horizontally, as shown at 2, and disposed a slight distance below the tread surfaces of the walls of the adjacent rails, as shown in Fig. 2 of the drawings. The larger or outer ends of the blocks 1 rest upon U-shaped brackets 3, which extend between the adjacent intersecting rails of the main track and siding, and have their opposite sides, designated 4, secured to the webs of the adjacent intersecting rails in any suitable manner, and as shown in Fig. 2 of the drawings. The outer ends of the blocks 1 are secured to the bracket 3 by means of bolts 5, which extend through openings 6 in the brackets and through openings in the lower or outer ends of the blocks 1, and nuts 7 are turned on the upper ends of the bolts and adjusted against the upper surface of the lower ends of the blocks 1, as shown in Fig. 2. The blocks 1 are formed of resilient metal, and are capable of withstanding considerable weight. The inner or smaller ends of the blocks 1 are provided with downwardly extending rectangular shaped heads 8, which are adapted to engage beneath the under surface of the balls of the intersecting rails of the main track and the siding, so as to limit the upward movement of the blocks 1. Interposed between the intersecting rails of the tracks A and B, as shown in Fig. 1, and the adjacent guard rails D and E, is a pair of foot blocks designated, respectively, 9 and 9^a. Each of the blocks 9 and 9^a consists of a plate formed of resilient metal and has one end secured to the horizontal arm of a substantially L-shaped bracket 10, one of the brackets being shown in Fig. 5 of the drawings, and the vertical arm of the bracket being secured to the web of one of the adjacent intersecting rails, as shown in Fig. 1. The blocks 9 and 9^a are bent upwardly from their secured ends, as shown at 11, and then extended horizontally, as at 12, in the direction of the point of intersec-

2
 tion between the rails of the tracks A and B, and reduced and terminally provided with depending rectangular shaped heads 13, the opposite ends of which extend beyond the sides of the free ends of the blocks 9 and 9^a and underlie the adjacent sides of the balls of the intersecting rails and the guard rails, and are adapted to engage the same so as to limit the upward movement of the free ends of the blocks 9 and 9^a. The blocks 9 and 9^a have those sides which oppose the usual deflected ends of the guard rails D and E, provided with lateral extensions 14, which lie in close proximity to the deflected ends of the guard rails D and E and fill the space between the deflected ends of the guard rails and the intersecting rails.

The guard rail F is provided with the usual deflected ends, and interposed between the deflected ends of the guard rail F and the adjacent rail of the track A is a pair of foot blocks 15, which, like the blocks 1, 8 and 9, are formed of resilient metal plates. Each of the blocks 15 has one end provided, as shown in Fig. 3, with a vertical flange 16 formed integral with one side edge thereof, and has connection with the web of the adjacent track rail, in any suitable manner. The blocks 15 are bent upwardly adjacent the flanged ends, as shown at 17, and then extended horizontally, as at 18, and the free terminals of the horizontally extended portions 18 are provided with depending rectangular shaped heads 19, the opposite ends of which project beyond the sides of the free ends of the blocks and engage beneath the balls of the tracks and guard rails for limiting the upward movement of the blocks 15. The blocks 15 are also provided with lateral extensions 20, which fill the spaces between the track rail and the adjacent deflected ends of the guard rail F.

It will be noted, by referring to the drawings, that the horizontal portions of the free ends of the blocks lie in close proximity to the tread surfaces of the rails of the tracks A and B, so that the same will be engaged by the wheel flanges of the car trucks during the passage of rolling stock over the points of intersection between the tracks of

the main rail and the side line, the engagement between the flanges of the wheels and the free ends of the blocks resulting in depression of the free ends of the blocks so as to prevent the tread surfaces of the wheels from being raised from engagement with the tread surfaces of the balls of the rails. By virtue of having the free ends of the blocks lying in close proximity to the tread surfaces of the balls of the rails of the tracks danger of an object or the foot of a person becoming wedged between either the intersecting rails of the main line and side line, or between the guard rails and the adjacent track rails will be overcome.

It is evident that various changes might be resorted to in the construction, form and arrangement of the several parts without departing from the spirit and scope of the invention as claimed.

Having thus described my invention what I claim as new, is:

1. A foot block adapted to be located between the intersecting rails of a switch frog or between one of the rails of a track and a guard rail, including a plate formed of resilient metal being bent to provide an upwardly extending portion, a horizontally disposed compressible portion adapted to lie in close proximity to the upper side of the walls of the adjacent rails, and a lateral extension formed on one of the side edges of the horizontal portion the terminal of the upwardly extending portion provided with a head adapted to engage beneath the balls of the rails limiting the upward movement of the upwardly extending portion, and means for securing the horizontal portion to the web of the rails.

2. A foot block adapted to be located between the intersecting rails of a switch frog or between one of the rails of a track and a guard rail and including a resilient compressible plate having one end provided with a flange for attachment with one of the rails.

In testimony whereof I affix my signature in presence of two witnesses.

JOHN J. LALLY.
